DESIGN FOR A PIN RECEPTACLE

Dudley M. Gould, New York, and Alexander
E. Lewis, Brooklyn, N. Y.

Application November 15, 1947, Serial No. 142,554

Term of patent 7 years

(Cl. D86—10)

To all whom it may concern:

Be it known that we, Dudley M. Gould and Alexander E. Lewis, the first named being a citizen of the United States and the second named being a subject of the King of Great Britain and being residents, respectively, of the city, county, and State of New York, and of the Borough of Brooklyn, county of Kings, city and State of New York, have invented a new, original, and ornamental Design for a Pin Receptacle, of which the following is a specification, reference being had to the accompanying drawing, forming a part thereof.

On the drawing:

Figure 1 is a top plan view of a pin receptacle, showing our new design.

Figure 2 is a side view in elevation of the receptacle shown in Figure 1.

Figure 3 is an end view in elevation of the pin receptacle.

We claim:

The ornamental design for a pin receptacle, as shown.

DUDLEY M. GOULD.
ALEXANDER E. LEWIS.
